UNITED STATES PATENT OFFICE

146,741

DESIGN FOR A PULL TOY

Clarence H. Keller, Buffalo, N. Y., assignor of
one-third to Norbert P. Floss and one-third to
Henry W. Rust, both of Buffalo, N. Y.

Application March 28, 1946, Serial No. 128,013

Term of patent 7 years

(Cl. D34—15)

To all whom it may concern:

Be it known that I, Clarence H. Keller, a citizen of the United States, residing at Buffalo, in the county of Erie and State of New York, have invented a new, original, and ornamental Design for a Pull Toy, of which the following is a specification, reference being had to the accompanying drawing, forming part thereof.

In these figures:

Fig. 1 is a perspective elevational view of a pull toy embodying my new design, this view being taken from the front and left thereof.

Fig. 2 is a rear end elevational view thereof and taken from the end opposite that shown in Fig. 1.

Fig. 3 is a left side elevational view thereof taken from the side opposite that shown in Fig. 1.

Fig. 4 is a bottom elevational view of Fig. 3.

I claim:

The ornamental design for a pull toy, as shown.
CLARENCE H. KELLER.
